UNITED STATES PATENT OFFICE

ROLAND J. OLANDER, OF CHICAGO, ILLINOIS, ASSIGNOR TO W. H. MINER, INC., OF CHICAGO, ILLINOIS, A CORPORATION OF DELAWARE

ANTIFRICTION BEARING

Application filed May 12, 1928. Serial No. 277,302.

This invention relates to improvements in anti-friction bearings.

One object of the invention is to provide an anti-friction bearing especially adapted for use as a side bearing member for railway cars, of simple construction, wherein the anti-friction element proper is self-centering under the influence of gravity, is positively guided to centered position, and is held against chattering in all of its operative positions.

Another object of the invention is to provide an anti-friction side bearing for railway cars, including a rolling anti-friction element which is self-centering, and a retaining housing for the anti-friction element provided with a hardened steel bearing plate on which the anti-friction element rolls, the plate having upstanding centering knobs or lugs pressed therein which cooperate with bearing openings or pockets in the anti-friction element, wherein the housing is open at the bottom to permit insertion of the anti-friction element and bearing plate, the bottom opening being closed by a separable plate secured thereto, thereby retaining the parts in assembled relation, the anti-friction element having shouldered engagement with the housing to prevent removal thereof through the top of the housing.

Other and further objects of the invention will more clearly appear from the description and claims hereinafter following.

In the drawings, forming a part of this specification, Figure 1 is a vertical, sectional view through portions of the body and truck bolsters of a railway car, illustrating my improvements in connection therewith, the anti-friction element being shown in full lines in its centered position and in dotted lines in the position assumed at the end of its travel in one direction. Figure 2 is a top plan view of the bearing member shown in Figure 1. And Figure 3 is a vertical, transverse, sectional view, corresponding substantially to

the line 3—3 of Figure 2, the anti-friction element being illustrated in elevation.

In said drawings, 10 denotes the under side portion of the body bolster of a railway car, and 11 the upper portion of an opposed truck bolster. In the present instance, my improved anti-friction bearing is illustrated as secured to the truck bolster.

My improved anti-friction bearing comprises, broadly, a retaining housing A; an anti-friction element B; a bearing plate C; and a separate bottom plate D for closing the bottom of the housing.

The retaining member or housing A is provided with vertical, spaced side walls 12—12 and transversely disposed, vertical, spaced end walls 13—13. At the bottom, the housing is provided with laterally projecting securing lugs 14—14, two lugs being disposed on one side of the housing and a third lug on the opposite side thereof.

The lugs are provided with the usual rivet-receiving openings and rivets 15—15 are employed to secure the housing to the top of the truck bolster 11, as clearly shown in Figure 1. The side walls 12 of the housing are provided with inwardly projecting retaining flanges 16—16 at the top thereof, the retaining flanges 16 having a thickened central portion 17 providing a depending retaining section. The bottom edge of each of the flanges 16 is disposed substantially horizontally at the opposite ends of the housing and the central portion of the lower edge of said flange immediately adjacent thereto is inclined downwardly in opposite directions, as indicated at 18—18, for a purpose hereinafter described. The side walls 12 and the end walls 13 are interiorly cut away at the bottom of the housing, thereby presenting upwardly inclined abutment faces 19—19, the abutment faces 19 of opposite side walls converging upwardly.

As shown, the housing A is open both at the top and bottom, and the bottom is

closed by the plate D, which, as shown, is relatively thick. The same is preferably composed of malleable iron. The plate D comprises a substantially flat central body portion, provided with corner lugs 20—20, which, as shown, are of greater thickness than the body portion of the plate. The lugs 20 are so arranged as to be disposed in the corners of the housing, and between the lugs 20, at opposite ends of the housing, the plate D is cut away, as indicated at 21, to provide openings through which cinders and other foreign matter which may accumulate in the housing is discharged.

The end walls 13 of the housing are also provided with discharge openings 22—22 in alignment with the cut-away portions 21 of the bottom plate. The side and end edges of the bottom plate are upwardly beveled, as indicated at 23, so as to fit the abutment wall sections 19 of the side and end walls of the housing. Adjacent the cut-away section 21, at one side of the housing, as indicated at 24—24 in Figure 2, the bottom plate D is undercut so that upon upsetting the corresponding lower edges of the end walls inwardly the bottom plate will be retained in locked position by the overlapping wall sections thus provided. One of the longitudinal side edges of the bottom plate D is also undercut, as indicated at 25 in Figure 3, and the corresponding side wall 12 is inwardly offset to overlap this section to lock the plate to the housing. The bottom section of the wall 12 is offset by hammering the same over to displace the metal at the lower edge thereof in overlapping relation with the bottom plate D. As clearly shown in Figures 1 and 2, the thickened lug members 20 of the bottom plate D provide transversely disposed aligned abutment faces 26—26, which cooperate with the bearing plate C to retain the same in proper position when the parts of the anti-friction bearing are assembled.

The bearing plate C is preferably formed of hardened steel and pressed to the shape shown. The plate C is of substantially rectangular outline and is provided with a pair of upstanding knobs or centering lugs 27—27, which are of substantially spherical formation.

The bearing plate C is of such a size as to fit between the abutment shoulders 26 of the bottom plate D at opposite ends of the housing and is of substantially the same width as the interior of the housing between the side walls 12.

The anti-friction bearing element B, as shown, is in the form of a rocker of substantially triangular cross section, having curved bearing surfaces. The rocker is provided with three curved bearing surfaces 28—28—28 of relatively long radius and three curved bearing surfaces 29—29—29 of

shorter radius. As shown, the bearing surfaces 28—28—28 are arranged in series and the bearing surfaces 29—29—29 of shorter radius connect each two adjacent bearing surfaces 28, the surfaces 29 merging with the surfaces 28.

With the conformation of rocker or bearing element B provided, the same is positively centered under the influence of gravity and, due to the arrangement of concentric surfaces of different radii in series, as hereinbefore described, the rocker or bearing element B, in its movement from the normal centered position to either side thereof, will have the bearing surface, which is disposed uppermost, spaced a constant vertical distance from the point of contact of the rocker or bearing element with the supporting bearing plate C.

In order to maintain the rocker bearing element B assembled with the housing, the same is provided with retaining projections 30—30 on the opposite sides thereof.

As shown in Figure 1, the retaining projections are of substantially triangular outline, having inclined side edges 31—31 converging upwardly and terminating in a curved connecting top edge face 32. As shown, the projections 30 engage under the retaining ribs or flanges 16 of the side walls of the housing, and the curved end edges 32 are slightly spaced from the depending sections 17 of the flanges when the anti-friction element is in normal centered position. When the anti-friction element B is rocked to either side of its centered position, one of the side edges 31 of each of the retaining projections is brought into opposed relation to one of the inclined wall sections 18 of the enlargement 17 of the corresponding flange 16, as clearly shown in dotted lines in Figure 1. The parts are so proportioned that substantially the same amount of clearance is provided at all times between the edges of the retaining projections 30 and the lower edges of the retaining flanges 16 of the housing. By this arrangement, rattling or chattering of the anti-friction element is effectively prevented in all operative positions of the same.

The bottom bearing surface 28 of the anti-friction element B which cooperates with the bearing plate C is provided with a pair of spaced centering openings or pockets 33—33 which are adapted to cooperate with the centering projections 27 of the bearing plate C.

By engagement of the bearing projections or knobs 27 of the plate C within the pockets 33 of the anti-friction element B, shifting of the rocker or bearing element in a longitudinal direction is positively prevented and the same is compelled to rock or roll to its centered position, as shown in Figure 1.

In assembling the parts of my improved anti-friction bearing, the anti-friction rocker

element B is first inserted through the open bottom section of the housing and the bearing plate C is placed in position on the bottom plate D, and the bottom plate inserted 5 within the bottom opening of the housing. When the bottom plate D has been forced into engagement with the abutment faces 19 of the walls of the housing, the bottom edge sections of the end walls and one of the side 10 walls are hammered over, as hereinbefore described, to lock the plate D in position. The parts of the side bearing are thus held in assembled relation and the anti-friction element B is prevented from escape through the 15 top of the housing by engagement of the retaining lugs 30 with the flanges 16.

In the operation of my improved anti-friction bearing, upon relative approach of the body and truck bolsters, the load is transmitted 20 through the anti-friction rocker element B, and upon relative angular movement of the body and truck bolsters the anti-friction element B is rolled to one side of centered position, as indicated in dotted lines in 25 Figure 1. The displacement of the anti-friction element continues either until the bolsters are separated or movement of the anti-friction element is limited by engagement with one of the end walls 13 of the housing, 30 as clearly indicated in Figure 1. When the bolsters are separated and the load removed from the anti-friction element B, the same returns to its normal centered position under the influence of gravity, due to the center of 35 gravity being displaced to one side of the vertical central axis of the anti-friction element.

From the preceding description, taken in connection with the drawings, it will be evident 40 that I have provided an exceedingly simple and efficient side bearing composed of only four parts, so designed as to require a minimum amount of labor in forming the parts and assembling the same, thereby 45 greatly reducing the cost of manufacture. The necessary foundry operations in casting the parts are also greatly reduced by avoiding the use of the usual retaining pin for the anti-friction element. The anti-friction 50 rocker element is thus left solid, that is, it is not provided with a pin receiving opening and the housing walls are left intact by omitting the retaining pin guide openings. The housing and anti-friction rocker element 55 may thus be cast without the use of the usual cores which are necessarily employed in these foundry operations, thus further reducing the cost of manufacture. The manner of assembling my improved bearing also avoids 60 all riveting for holding the parts assembled.

The employment of the stamped, hardened steel bearing plate for the anti-friction rocker element, not only simplifies the construction by elimination of the separate rivet members 65 commonly used in bearings of this type,

wherein the rivet members have centering heads or knobs thereon and are formed of relatively soft material, but also adds greatly to the life of the bearing member and its efficient operation, especially in that the bearing projections are formed of the same hardened material as, and form a part of, the hardened bearing plate. 70

While I have herein shown and described what I consider the preferred manner of carrying out my invention, the same is merely illustrative and I contemplate all changes and modifications which come within the scope of the claims appended hereto. 75

I claim:

1. In an anti-friction bearing for railway cars, adapted to be interposed between the body and truck bolsters thereof, the combination with a housing open at the top, said housing being provided with inwardly overhanging retaining flanges at the top, having depending central projections having bottom portions inclined upwardly in opposite directions; of an anti-friction rocker element within the housing, said rocker having retaining projections on the opposite sides thereof, adapted to engage beneath said flanges to prevent escape of the rocker through the open top of the housing, said retaining projections being of triangular formation and each having upwardly converging side edges connected at the top by a curved edge engaged beneath the central portion of the depending projection of the corresponding flange of the housing when the 90 rocker is in centered position and having one of said converging side edges engaged beneath the inclined bottom edge at one side of the center of said projection when said rocker is displaced to one side of its normal 95 centered position, said curved edges and said side edges being respectively equally spaced from the flanges of the housing when said anti-friction element is in said respective centered and displaced positions. 100

2. In a side bearing, the combination with a housing having end and entirely closed side walls, the latter being provided on their inner faces with guide flanges; of a rolling, gravity, self-centering, solid anti-friction element; a bearing plate having upwardly extending integral stud formations, said element having cooperating recesses within which the studs are received and relative bodily shift between said element and plate is prevented, said anti-friction element having integral projecting wings engaging beneath the flanges of the side walls of the housing to limit upward displacement of the element in all positions thereof and preventing disengagement of said studs; and a bottom closure plate for the housing having integral projections between and by which said bearing plate is retained in centered position, said bottom plate being secured 110 115 120 125 130

to the housing by peening portions of one
against the other whereby said housing, anti-
friction element, bearing plate and bottom
plate may be assembled entirely by hand and
all permanently retained in operative as-
sembled position, one with the other, solely
by and upon the peening together of said
bottom plate and housing.

In witness that I claim the foregoing I
have hereunto subscribed my name this 9th
day of May, 1928.

ROLAND J. OLANDER.
